UNITED STATES PATENT OFFICE.

ALDRICH L. JACKSON, OF ST. PAUL, MINNESOTA, ASSIGNOR TO FEDERAL MANUFACTURING COMPANY, A COPARTNERSHIP CONSISTING OF FRED C. NACHTIGALL, OTTO A. BLUME, AND ALDRICH L. JACKSON, OF ST. PAUL, MINNESOTA.

DESIGN FOR AN ADVERTISING CIGAR LIGHTER.

Application filed March 16, 1927. Serial No. 21,158. Term of patent 3½ years.

To all whom it may concern:

Be it known that I, ALDRICH L. JACKSON, a citizen of the United States, residing at St. Paul, in the county of Ramsey and State of Minnesota, have invented a new, original, and ornamental Design for Advertising Cigar Lighters, of which the following is a specification, reference being had to the accompanying drawings, forming part thereof.

I claim:

The ornamental design for an advertising cigar lighter, as shown.

ALDRICH L. JACKSON.
